AIR COMPRESSION SYSTEM OF VARIABLE
RADIATION CAPACITY

Lyndon F. Wilson and John M. Lammedee, Chicago, Ill., assignors to Wilson Engineering Corporation, Chicago, Ill., a corporation of Delaware

Application August 31, 1938, Serial No. 227,696

4 Claims. (Cl. 303—1)

This invention relates in general to compressed air systems, and while the principles thereof may be utilized in compression systems designed for various uses, they are particularly applicable to 5 air compression systems for railway train use. Compressed air is commonly employed for operating and controlling the brakes and some other equipment on railway trains, trolleys, busses, and other vehicles on which the compressed air system employed is continuously exposed to the surrounding atmospheric temperatures. The atmospheric air taken into the compressor varies widely not only in temperature but in humidity. Consequently, the condition of the 10 air when compressed varies accordingly in temperature and humidity.

Condensation in a compressed air system becomes of vital importance where the system is subjected to freezing temperatures for the reason 15 that if the condensate freezes in the line beyond the storage reservoir or at the control valves, the system is rendered immediately inoperative, and serious accidents as the result of brake application failure may result. A similar hazard is, of course, presented if the condensate freezes in the 20 line ahead of the storage reservoir, that is, between the compressor and the reservoir.

In order to prevent condensation and consequent freezing in the supply line from the reservoir, modern practice requires that the compressed air be cooled enroute to the reservoir so that it will reach approximately its lowest temperature in the reservoir where the condensate 25 may be collected and drained off without interfering with the operation of the system. With this end in view, an air cooled radiator or cooler is customarily interposed in the line between the compressor and the reservoir, but in order to insure against the freezing up of this line as the 30 result of production of excessive condensation therein, the capacity of the radiator is so limited that when subjected to the lowest expected atmospheric temperature, the compressed air and condensate will still enter the reservoir at a temperature 35 above freezing.

As a result of this restricted radiator capacity, the system when operating under high atmospheric temperatures is very inefficient because 40 the temperature of the atmospheric air taken into the compressor is raised substantially by the act of compression, and since the radiator capacity is, for the reason above mentioned, insufficient to dissipate all or even a large part of the 45 heat of compression, the air enters the reservoir

considerably above atmospheric temperature. The effective capacity of the reservoir is accordingly diminished in accordance with the increased temperature, and the air in the supply line from the reservoir being further cooled enroute to its 5 point of use loses pressure as it is reduced in temperature, thereby becoming less effective for the required operating purposes.

The ideal condition for hot weather operation is to dissipate all the heat of compression before 10 the air reaches the reservoir, and for cold weather operation to dissipate only so much of the heat of compression as will leave the air and condensate entering the reservoir at a temperature slightly above freezing so as to obviate danger of stop- 15 page by freezing of the supply pipe to the reservoir.

The purpose of our present invention is to approach as nearly as practicable such ideal operating conditions by providing a variable capacity 20 radiator which, under cold weather operation, will dissipate only a safe amount of heat from the compressed air, and in hot weather operation will, due to its increased capacity, dissipate as much as possible of the heat of compression 25 before the compressed air enters the reservoir.

On the accompanying drawing, we have shown for illustrative purposes merely those embodiments of our invention which at present appear to be most practical, but it should be understood 30 that these embodiments are illustrative merely and are not intended to circumscribe the scope of our invention as defined in the claims.

Referring to the drawing:

Fig. 1 is a plan view somewhat schematic in 35 character of a compression system embodying our invention;

Fig. 2 is a sectional view on the line 2—2 of Fig. 1; and

Fig. 3 is a similar view of a modified form of 40 the invention.

Referring to the drawing more in detail, reference character 5 indicates generally an air compressor of any standard or preferred type which may be electrically or otherwise driven, a steam 45 actuated motor being here illustrated as the driving means. The compressed air storage reservoir indicated by reference character 7 may be of any preferred shape and dimensions, the compressed air from this reservoir being delivered to 50 the point of use through a delivery pipe 8. Condensation accumulating in the reservoir may be drawn off at intervals through the cock 9.

The compressed air is delivered to the reservoir from the compressor through a pipe line 55

11 which, in accordance with our invention as exemplified in Fig. 1, is divided between the compressor and the reservoir into two branches 12 and 13 in each of which is interposed a radiating unit or cooler 14 exposed to atmosphere and adapted to dissipate heat of compression from the compressed air passing therethrough.

5 While the radiating units may be of any preferred construction, we have shown here for 10 illustrative purposes an efficient and satisfactory type of unit comprising a relatively narrow body 15 of cast iron or the like equipped with a series of radiating fins 16 cast integrally with the body and preferably formed of a high heat conductivity material such as aluminum. These units are designed to efficiently dissipate the excess heat from the compressed air enroute from the compressor to the storage reservoir.

15 It will be observed that in Fig. 1 the units are 20 shown as interposed in the supply line in parallel so that substantially equal proportions of the compressed air will pass through each unit when the plug valve 17 in the branch 13 is open.

25 For hot weather operation, this valve is open 30 so that the full radiating capacity of the two units may be utilized. These units constitute in effect a single large heat dissipating radiator interposed in the supply line to the reservoir. The aggregate radiating capacity of the units illustrated is such that substantially all of the heat 35 of compression is dissipated from the air. The air accordingly is delivered to the reservoir at substantially atmospheric temperature which contributes maximum efficiency. If, because of 40 space limitations or other reasons, two radiator units are insufficient for the required purposes, one or more additional branch pipes equipped with similar units may be connected in the line between the compressor and the reservoir.

45 In other words, our invention contemplates the utilization of as many heat radiating units as may be necessary or desirable in any particular installation, and any or all of them may be equipped with shut-off valves so that the capacity of the radiator as a whole may be varied to 50 meet existing conditions by shutting off one or more of the valves to thereby reduce the radiating capacity.

55 In the form of the invention shown in Fig. 3, the two radiator units 14, illustrated, instead of being connected in the supply line 11 in parallel 55 are connected in series, and a shunt line 18 around one of the units is controlled by a three-way valve 19 by manipulation of which the compressed air may be delivered directly through both units for hot weather operation or shunted around one unit for cold weather operation. Additional radiator units may also be employed in this type of hook-up, and shunt lines and valves 60 may be employed to cut out one or more of such units as occasion requires.

It should be apparent from the foregoing that we have provided an air compression system having a variable radiation capacity which can be regulated and controlled so as to conform to atmospheric temperature variations and produce a maximum efficiency in operation under all conditions and without danger of injury as the result of freezing of the system.

5 The structural details shown for illustrative purposes may obviously be varied within wide 10 limits without exceeding the scope of the intended claims.

We claim:

1. A variable radiation air compression apparatus for railway air brake systems comprising, 15 an air compressor; a compressed air storage reservoir for supplying air to a braking apparatus; and means for unobstructedly delivering compressed air from the compressor to the reservoir and for cooling said air en route, said means including a plurality of radiation units, a pipe system, and a control valve whereby the air may be directed through one or more of said units to vary the radiation capacity of said system at will.

20 2. In a system for supplying compressed air for braking purposes, the combination of: a compressor; a storage reservoir for compressed air; a plurality of heat radiating units and piping connecting said heat radiating units in parallel between said compressor and reservoir for cooling the compressed air en route to said reservoir; and a valve connected in said piping arranged to control the flow of compressed air to one of said heat radiating units, whereby the flow of compressed air through said unit may be 25 cut off.

3. A system for supplying compressed air for braking purposes comprising, a compressor; a reservoir for compressed air; a plurality of heat 30 radiating units; piping connecting said heat radiating units in series between said compressor and reservoir; a shunt pipe line around one of said heat radiating units connected with said piping; and a valve connected with said shunt line and disposed between two heat radiating units for cutting out one of said heat radiating units and directing flow through said shunt line.

35 4. In a system for supplying compressed air for braking purposes, the combination of: a compressor; a storage reservoir for compressed air; a plurality of heat radiating units and piping connecting said heat radiating units with said compressor and reservoir for cooling the compressed air en route to the reservoir and a valve connected in said piping arranged to control the flow of compressed air to one of said heat radiating units, whereby the flow of compressed air through said unit may be cut off.
